(57) **CLAIM**

The ornamental design for a bicycle stem, as shown and described.

DESCRIPTION

FIG. 1 is a perspective view of the bicycle stem, showing my new design in which the rear end and tube are shown in broken lines which form no part of the claimed design;

FIG. 2 is a front elevational view thereof;

FIG. 3 is a side elevational view thereof, of which the opposite side is a mirror image;

FIG. 4 is a bottom plan view thereof; and,

FIG. 5 is a top plan view thereof.
